UNITED STATES PATENT OFFICE.

JOSEPH H. ELLINGSWORTH, OF EAST MOLINE, ILLINOIS.

PARCEL PARACHUTE.

Application filed December 24, 1925. Serial No. 77,570.

My invention has reference to parcel parachutes, and is similar in character, and makes use of some of the parts, of a parachute for which I have filed an application for Letters Patent of the United States, Serial No. 10,485, under date of Feb. 20, 1925. The present invention is of special use in dropping packages of mail from an air-ship, but it is equally useful for carrying other small parcels downwardly to a safe landing. By its use the necessity of making a landing every time it is desired to make a delivery of mail or the like is done away with.

The invention consists primarily in providing a small parachute for each package to be discharged, such parachute being stored in a container, from which it is automatically released upon the package being dropped overboard. Connected therewith is a contrivance for compelling the satisfactory opening of the parachute, such as is set forth in said former application.

Another feature thereof is the provision of means for illuminating the parachute coincidently with its discharge, so that its course will be observable under conditions of darkness.

The above-named, and other features and advantages of the invention will more fully appear from the following specification, reference being had to the accompanying drawings, in which:—

Fig. 1 shows the rear portion of the fuselage of an airship, with the invention attached thereto.

Fig. 2 shows the invention in longitudinal section.

Fig. 3 is a sectional view of the parachute, distended.

Fig. 4 is an enlarged detail of the discharge end of the casing 3.

The reference number 1 indicates a fragmentary part of the body of an air-ship, and 2 the cock-pit thereof. 3 is a cylindrical casing, of slightly tapered form, and provided at its small end with a cylinder 4 of reduced size, in which is slidable a rod 5, on the outer end of which is a ring 6, connected with a ring 7 attached to the side of the airplane. Fixed to said rod within the casing 5 is a disk 8, and on the inner end of said rod is a head 9. 10 is a cylinder of suitable shape and size to be received in the large end of the casing 3, and provided with a rolled end 11, to which is fixed a catch 11^a,

for engagement with an annular bead 3^a on the outer face of the casing 3. By this means the cylinder 10 is held removably in place.

Within the casing 10 is a parachute 13, packed in a compact manner, and having cords 14 attached to its edge, said cords being connected with a ring 15 on the end of a rod 16, on which is slidable a plug 17, forming a closure for the end of the tube 10. Fixed to the inner end of the rod 16 is a catch formed of a plurality of arms 18, provided at their ends with feet 19 which have a frictional engagement with the wall 70 of the casing 10, and prevent accidental release of the plate 17. The arms 18 are formed of resilient material, and when force is applied to the rod 16 to draw the same outwardly, the arms 18 spring outwardly 75 until the catch is released, permitting its escape from the tube 10, together with the plug 17. A coiled spring 20 connects the plug 17 with the rod 16, at a point near the catch 18, such spring tending to hold the 80 plug in its position in the tube. As the rod is drawn outwardly the spring is compressed, and the plug forced from its seat.

The cylinder 3 is held normally in a horizontal position by means of a spring catch 85 21, and fixed to said cylinder is a ring 22, from which a chain 23 leads upwardly into the cock-pit. It is thereby possible for the operator to release the cylinder 3, and raise the large end thereof to a point near the 90 cock-pit, for the purpose of inserting the tube 10, or removing the same. A chain 24 also leads from the cock-pit to a ring in the end of the rod 16, the other end of said chain being attached to a bundle of mail or 95 other package in the cock-pit.

When it is desired to drop a parcel from the air-ship, it is merely cast over-board, the weight of the parcel operating to pull the cylinder 3 downwardly, releasing the same 100 from the catch 21, and swinging it into a vertical position. The weight of the package then draws the catch 18 and plug 17 outwardly, these being followed by the parachute, which gradually opens, in manner 105 described in said former application, the upper part of the parachute being retarded by the partial vacuum caused in the upper end of the cylinder 3, through the action of the piston 8 in the casing 4. The parachute 110 and its load then descend gradually to the ground.

For convenience a number of the parachutes may be employed, each in its own container 10, and each attached to its particular load. After a parcel has been discharged the cylinder 3 is raised and the casting 10, which remains in the cylinder, is replaced with another one. These cylinders may be of different sizes, to suit the size of the package with which they are used, and the parachutes will be similarly varied as to size.

A light bulb 25 is supported from the under side of the parachute, and connected by wire with a small electric battery 26 on 15 the inner face of the plug 17, the battery being provided with a switch controlled by a pin 27, actuated by one of the arms 18 when the catch is released, turning on the light in the bulb. This is for use when a package 20 of mail is to be discharged under conditions of darkness, the illuminated parachute enabling watchers to follow its course to the earth, and secure same. The usual signals will be provided for informing the operator 25 of the plane as to his location, and the points at which the mail or other parcels are to be discharged.

It will be observed that by the use of the invention a great deal of time will be saved, 30 as the air-man can keep steadily on his course, dropping the various packages of mail at the places for which they are destined.

What I claim, and desire to secure by 35 Letters Patent, is:—

1. A device of the class described, comprising a cylinder adapted to be swingingly supported at one of its ends to the side of an air-ship; a tubular member removably held in the movable end of said cylinder; and a parachute contained in said tubular member, and capable of discharge therefrom by the weight of an object attached thereto.

2. A device of the class described, comprising a cylinder, adapted to be swingingly attached to the body of an air-ship; a tubular member adapted to be removably held in said cylinder; a parachute packed in said tubular member so as to distend upon leaving the same; a closure for said tubular member, connected with said parachute; means for holding said parachute against accidental release from said tubular member; and means for attachment to said para-

chute of a parcel, the weight of which will 55 operate to discharge the parachute from its container.

3. A device of the class described, comprising a receptacle adapted for attachment to the body of an air-ship, having a discharge end capable of being directed downwardly; a container removably held in the discharge end of said receptacle; a parachute folded in said container so that the top thereof will be the last to leave the same; 60 means in said receptacle for retarding the release of the top of said parachute; and means for attachment to the parachute of an object, the weight of which will cause the release of the parachute from the container. 70

4. A device of the class described, comprising a cylinder adapted to be swingingly supported at one of its ends to the side of an air-ship; a tubular container removably held in said cylinder; a parachute folded 75 in said container so as to be discharged by the weight of an object attached thereto; a lighting element carried by said parachute; and means for illuminating said lighting element, set in operation upon said parachute 80 being discharged from said container.

5. A device of the class described, comprising a cylinder adapted for attachment at one of its ends to the body of an air-ship; a flexible connection for the free end 85 thereof, by means of which it may be raised or lowered; means for holding said cylinder normally in a horizontal position; a tubular container removably held in said cylinder; a parachute folded in said container 90 so as to distend upon leaving the same; and a closure for said container, connected with said parachute, and means for attachment thereof to a parcel, the weight of which will withdraw the parachute from the container. 95

6. A device of the class described, comprising a cylinder adapted to be pivotally attached to the body of an air-ship at one of its ends; a tubular container removably held in the movable end of said cylinder, 100 adapted to hold a parachute in compact form; and air-exhausting mechanism at the pivotal end of said cylinder, capable of operation upon said cylinder being swung into position for discharging a parachute from 105 said container.

In testimony whereof I affix my signature.
JOSEPH H. ELLINGSWORTH.
